CLAIM

The ornamental design for a hand mixer, as shown and described.

DESCRIPTION

FIG. 1 is a top, front and right side perspective view of a hand mixer, showing our new design;

FIG. 2 is a front elevation view thereof;

FIG. 3 is a right side elevation view thereof;

FIG. 4 is a rear elevation view thereof;

FIG. 5 is a top plan view thereof;

FIG. 6 is a left side elevation view thereof;

FIG. 7 is a bottom plan view thereof; and,

FIG. 8 is a bottom, rear and left side perspective view thereof.

The broken lines shown in the figures are for the purpose of illustrating portions of the hand mixer and form no part of the claimed design.

1 Claim, 8 Drawing Sheets
